UNITED STATES PATENT OFFICE.

THADDEUS L. CUMMINGS, OF SPENCER, IOWA.

AUTOMATIC FRICTION-GOVERNOR IN FLY-WHEELS.

No. 809,784.

Specification of Letters Patent.

Patented Jan. 9, 1906.

Application filed May 28, 1904. Serial No. 210,298.

To all whom it may concern:

Be it known that I, THADDEUS L. CUMMINGS, a citizen of the United States, residing at Spencer, in the county of Clay and State of Iowa, have invented a new and improved automatic friction-governor in a fly-wheel for threshing-machine self-feeders or for any other machine where it is desired to gage the speed or stop the motion of the machine when the speed falls below that for which it is set, of which the following is a full, clear, and exact description.

My invention is a friction-governor; and it consists in certain novel constructions and combinations of parts hereinafter described and claimed.

Referring to the drawings forming a part hereof, Figure 1 is a front view of my invention. Fig. 2 is a view from the opposite side thereof. Fig. 3 is a vertical longitudinal section, and Fig. 4 is a view of the fly-wheel alone.

In the practical application of my invention I provide a fly-wheel B, keyed or otherwise secured to a driving-shaft A and comprising a hub and a peripheral ring connected thereto by four spokes. Two of the opposite spokes are provided with pins 12, engaging one of a series of holes G in curved levers E. The levers E are provided at corresponding ends with the balls 13. Cotter-pins 12^a secure the levers in place, and springs 14, secured at one end to the levers and at the other to hooks 15 on the hub, retain them normally in an inward position.

Rock-arms 18, pivoted upon brackets 20, projecting from the rear face of the above-named spokes, are provided with forwardly-extended arms 17 for engagement by the curved levers E. A spring 27, secured to bolts 28, traversing the free ends of the arms 17 and secured in place by nuts 29, maintains the arms in contact with the curved levers, while a projection 17^a overlaps the curved lever and retains it against the face of the fly-wheel. Inwardly-projecting arms 21 on the rock-shafts 18 are provided with brake-shoes 23, secured to plates 22 on said arms and adapted to engage the rear face of a disk C, loosely mounted on the driving member A. Upon the aforementioned spokes, adjacent to the brackets 20, plates 26 are secured, provided on their free faces with brake-shoes 25 for engaging the forward face 55 of the disk, and a sprocket-wheel D, integral

with the disk, transmits motion to the driven member.

When power is applied to the driving member, the fly-wheel is rotated, and when a predetermined speed is attained the balls are thrown outward against the resistance of their spring. The curved levers force the forwardly-extending portion of the rock-arms outward, pressing the brake-shoes on the inwardly-extending arms against the rear face of the disk and moving said disk into contact with the brake-shoes on the fly-wheel, thus locking the disk and fly-wheel together.

The degree of speed necessary to impart motion to the disk C may be varied by lengthening or shortening the end of the curved levers provided with the balls, the longer the lever the less centrifugal force required to move the balls outward.

It will be evident that when the speed of the fly-wheel falls below the predetermined point the disk will be released, while an increase of speed increases the strength of the grip.

What I claim is—

1. In an apparatus of the class described, the combination of a driving member, a fly-wheel secured thereto, oppositely-disposed forwardly-projecting pins on the fly-wheel, oppositely-disposed curved levers each provided with a series of perforations for engaging the pins, cotter-pins for securing the levers on the pins, springs normally retaining the levers in their inward positions, balls on the corresponding ends of the levers, oppositely-disposed rearwardly-projecting brackets on the fly-wheel, brake-shoes on the face of the fly-wheel adjacent to the brackets, rock-levers pivoted to the brackets and provided with forwardly-extending arms for engaging the levers, a spring connecting the forwardly-extending arms, inwardly-extending arms on the rock-shaft, and provided with brake-shoes, a disk loosely mounted on the driving member for engaging the brake-shoes on the fly-wheel and for engagement by the brake-shoes on the inwardly-extending arms of the rock-shafts.

2. In an apparatus of the class described, the combination of a driving member, a fly-wheel secured thereto, oppositely-disposed forwardly-projecting pins on the fly-wheel, oppositely-disposed curved levers each provided with a series of perforations for engag-

ing the pins, means for securing the levers on the pins, a spring for restraining the levers in their inward positions, balls on the corresponding ends of the levers, oppositely-disposed rearwardly-projecting brackets on the fly-wheel, brake-shoes adjacent to the brackets, and secured to the fly-wheel, rock-levers pivoted to the brackets and provided with forwardly-extending arms for engaging the levers, a spring connecting the forwardly-extending arms, inwardly-extending arms on the rock-shaft, a disk loosely mounted on the driving member, and means on the inwardly-extending arms of the rock-shaft for engaging the disk and forcing the same against the brake-shoes on the fly-wheel.

3. In an apparatus of the class described, the combination with a driving member, of a fly-wheel secured thereto, oppositely-disposed curved levers pivoted on the front face of the fly-wheel and provided with balls at their free ends, rearwardly-projecting brackets on the fly-wheel, rock-shafts pivoted in the brackets and each provided with a forwardly-extending arm for engaging the curved levers, brake-shoes secured to the fly-wheel adjacent to the brackets, a disk loosely mounted on the driving member, and means on the rock-shaft for engaging the disk and forcing the same into contact with the brake-shoes on the fly-wheel.

4. In a friction-governor, the combination of the driving member, a fly-wheel secured thereto, oppositely-disposed curved levers pivoted on the forward face of the fly-wheel and provided with balls at their free ends, rock-shafts pivoted on the rear face of the fly-wheel, means on the rock-shafts for

engaging the curved levers, a disk loosely mounted on the driving member, and means on the rock-shafts for engaging the rear face of the disk to force the same into contact with the fly-wheel.

5. In a friction-governor, the combination of the driving member, a fly-wheel secured thereto, weighted levers pivoted on the front face of the fly-wheel, rock-shafts pivoted on the rear face of the fly-wheel, a disk loosely mounted on the driving member, an arm on each rock-shaft for engagement by the weighted levers, and means on the rock-shafts for engaging the disk to force the same into contact with the fly-wheel.

6. In a friction-governor, the combination of a driving member, a fly-wheel secured thereto, a disk loosely mounted on the driving member, means on one face of the fly-wheel for forcing the disk into contact therewith, and means on the other face of the fly-wheel to actuate said engaging means, on the attainment of a predetermined speed by the driving member.

7. In a friction-governor the combination of a driving member, a fly-wheel secured thereto, a driven member adjacent to the fly-wheel, means on one face of the fly-wheel for engaging the driven member, and means on the other face for actuating said engaging means on the attainment of a predetermined speed by the driving member.

In testimony whereof I have signed my name to this specification in the presence of two subscribing witnesses.

THADDEUS L. CUMMINGS.
